A. SOLOSABAL

REFLECTOR

Filed April 23, 1923

INVENTOR.
Andres Sologabal

BY Albert C. Bell.

ATTORNEY.

UNITED STATES PATENT OFFICE.

ANDRES SOLOSABAL, OF BOISE, IDAHO.

REFLECTOR.

Application filed April 23, 1923. Serial No. 633,821.

To all whom it may concern:

Be it known that I, ANDRES SOLOSABAL, a citizen of the United States, residing at Boise, in the county of Ada and State of Idaho, have invented a new and useful Improvement in Reflectors, of which the following is a specification.

My invention relates to an improved construction of reflector for use in headlights and particularly for use in headlights for motor vehicles. In my improved reflector construction I provide upper and lower reflecting surfaces which are both preferably substantially surfaces of revolution. The principal difference between the upper and lower portions of the reflecting surfaces is that the lower portion is left a true surface of revolution and the upper portion is flattened preferably at successive portions to slightly break or interrupt the continuity of the true surface of revolution and thus interfere to a slight degree with what would otherwise be the reflecting action of that part of the surface of revolution. While the generating curve employed to form the surface of revolution is preferably a parabola, thus producing a paraboloid of revolution, I do not limit myself to this exact generating curve as any curve may be used for the purpose that will give the desired reflecting effect.

Another important feature of my invention is that I provide the reflector with an open end lying in a plane at an acute angle to the axis of revolution of the reflecting surface. This is for the purpose of permitting the open end of the reflector to be placed in close proximity to the front end of any desired headlight casing and substantially in parallel relation thereto, while at the same time the axis of the beam of light projected from the reflector shall be directed downwardly to illuminate the roadway, rather than being directed horizontally, for which condition a large part of the light from the reflector would not strike the roadway and would be ineffective and what is even more important, would be in a direction to produce a glaring effect in the eyes of pedestrians and the drivers of other vehicles. It will be understood that headlight casings are preferably mounted with their axes in horizontal position as this adjustment gives a more pleasing appearance than if the headlights as a whole, were directed down-

wardly, and with my improved construction of reflector, with the headlight casing mounted in a position such that its axis is horizontal and its front end is in substantially a vertical plane, although the open end of the reflector will also be in substantially a vertical plane, the axis of the projected beam of light is directed downwardly to prevent glare in the eyes of pedestrians and the drivers of other vehicles and with the desirable effect also of better illuminating the roadway than where the axis of the beam of light is substantially horizontal.

The upper portion of the reflecting surface of my reflector consists preferably of a plurality of slightly flattened surfaces adjacent to each other and covering substantially the entire upper half of the reflecting surface, the flattening effect being slight, and although the surface is still substantially a surface of revolution, the flattening is sufficient to prevent the projection from the upper half of the reflecting surface of an intensely concentrated beam of light, the flattened portions serving to diffuse the light somewhat, this diffusion being sufficient to prevent glare in the eyes of pedestrians and the drivers of other vehicles if the beam from the upper portion of the reflecting surface is directed high enough to strike pedestrians and the drivers of other vehicles.

My improved reflector construction provides also a means for securely holding an electric lamp in focusing position in the reflector and at the same time permitting motion of the lamp axially of the reflector to focus the lamp therein, the lamp being securely held in any desired position by means of an improved spring clamping device, as will be more fully explained in connection with the description of the drawings below.

My invention will best be understood by reference to the accompanying drawings showing a preferred embodiment thereof, in which

Fig. 1 shows my reflector in front elevation,

Fig. 2 is a sectional view of the construction shown in Fig. 1 taken along the line 2—2,

Fig. 3 is a sectional view of the reflector shown in Fig. 1 taken along the line 3—3, and

Fig. 4 shows in rear elevation the lamp

supporting tube projecting from the reflector and the relation of the lamp clamping mechanism thereto.

Similar numerals refer to similar parts throughout the several views.

As shown in Figs. 1 and 2 the reflector consists of a metal structure 10 having an inner reflecting surface which is preferably a surface of revolution described around the axis 11-11. The open front end of the reflector 10 is preferably in a plane as indicated at 12-12 in Fig. 2, forming an acute angle with the axis 11-11, as a result of which the mechanical axis of the reflector 15 is substantially as represented by the line 13-13.

As a result of the construction described, in mounting the reflector in a headlight casing in accordance with the usual practice, the surface 12-12 is made substantially parallel with the front end of the casing, thus bringing the mechanical axis 13-13 into horizontal position, for which condition the beam of light about the optical axis 25 11-11 of the reflector is projected downwardly by an amount equal to the angle between the axes 11-11 and 13-13. This downward projection of the beam of light may in some cases be sufficient to prevent 30 projecting the beam of light into the eyes of pedestrians and the drivers of other vehicles and eliminating undesirable glare in this connection and the effect furthermore is to better illuminate the roadway and thus 35 give greater certainty in connection with driving the vehicle on which the reflector is used.

To further insure pedestrians and the drivers of other vehicles against the undesirable glare referred to, I provide a second novel feature in my reflector consisting of slightly flattening the upper portion of the reflector as indicated at 10^a, 10^b, 10^c, 10^d and 10^e, these flattened sections of the reflecting surface being preferably adjacent to each other and extending vertically of the reflector from substantially the horizontal diameter thereof to the upper edge thereof. The effect of these flattened surfaces is illustrated in Fig. 3. Assuming the reflector surface to be a paraboloid of revolution, the mid portion of each flattened surface vertically, is substantially the same as though the flattened surfaces were not used and the rays projected from these mid portions vertically are projected in substantially parallel relation with the optical axis 11-11 of the reflector as indicated at 14^a, 14^b 45 14^c, 14^d and 14^e. It is further to be noted that the several rays projected from the mid portion vertically which lie in a vertical plane extending through said mid portion, are all projected in substantially parallel relation to the optical axis 11-11 of 50 the reflector as indicated at 14^e in Fig. 2 for

the flattened portion 10^e of the reflecting surface. The other rays reflected from each of the flattened portions are, however, non-parallel and diverge from each other as they leave the flattened surfaces, as indicated at 15^a, 15^b, 15^c, 15^d and 15^e in Fig. 3, the amount of this divergence for any section, depending upon the particular curvature of the reflecting surface and therefore the degree of flattening, which divergence 70 it will be understood, varies from top to bottom of each of the flattened surfaces. The result is that the beam of light projected from the upper portion of the reflector is a beam of thoroughly diffused light, 75 that the diffusion need not be great and therefore that the illuminating effect of this portion of the beam is maintained in a large degree and has the advantage of giving more widely spread illumination, than is afforded by the lower part of said beam; this is desirable since the upper portion of the beam is effective in illuminating the surroundings generally and the lower portion of the beam is effective in illuminating the 80 roadway. It will further be observed that I produce this desirable effect with a construction readily made and of extreme simplicity.

As is well known in operating reflectors 95 of the kind under consideration, it is of great importance that the lamp employed shall be at the focal point of the reflecting surface. As indicated in Fig. 2, I show an electric lamp 16 mounted in a tube 17 100 extending rearwardly from the reflector 10, the base 16^a of the lamp being preferably a free sliding fit in the tube. The tube 17 has cut through its wall a slot 17^a in which an annular spring 18 is disposed, said spring 105 extending through said slot, and thus slightly into the bore of the tube and held in place by having its ends extending around the tube on the outer surface thereof. The relation of these parts is more clearly shown in Fig. 110 4. As a result of the construction described, inserting the lamp 16 into the tube 17 moves the spring 18 outwardly from the bore of the tube 17 until the spring rests on the outer surface of the base 16^a of the lamp 115 and the lamp may then be readily moved in the tube to focus it. The spring 18 is strong enough to positively hold the lamp against accidental displacement, in whatever position it may be as a result of the 120 focusing operation.

While I have shown my invention in the particular embodiment above described, it will be understood that I do not limit myself to this exact construction, as I may employ equivalents known to the art at the time of the filing of this application without departing from the scope of the appended claim.

What I claim is:

A reflector comprising upper and lower reflecting surfaces each extending over substantially half of the total reflecting surface, said lower half surface being an unmodified paraboloid of revolution and said upper half surface consisting of a plurality of vertically extending zones, each of said zones being of parabolic conformation in vertical section and of flat conforma-
tion laterally of the reflector, the front edge 10 of said reflector being at an acute angle to the reflector axis inclining said axis downwardly when said front edge is in a vertical plane.

In witness whereof, I hereunto subscribe my name this 16th day of April, A. D. 1923.

ANDRES SOLOSABAL.
